LUBRICANT AEROSOL GENERATOR

Fred J. Everett, Chicago, Ill., assignor to Stewart-Warner Corporation, Chicago, Ill., a corporation of Virginia

Application June 25, 1957, Serial No. 667,839

5 Claims. (Cl. 183—24)

This invention relates to an improved aerosol generator.

The present invention is an improvement over the aerosol generator of the type shown in United States Patent 2,610,700, issued September 16, 1952, to Gothberg. The aerosol generator shown in the patent has gained widespread commercial use because of its highly efficient misting characteristics and also because of the high quality aerosol produced by the unit.

It is an object of the present invention to provide an even more efficient and improved aerosol generator.

It is a further object of the invention to provide a more efficient aerosol generator which produces a high quality aerosol.

A feature of the present invention is the provision of an annular oil delivery nozzle, an annular venturi surrounding the nozzle for the air stream of the aerosol generator and an expansion chamber immediately downstream from the venturi and the nozzle outlet.

Another feature of the present invention is the provision of a spring-biased air bypass providing a substantially constant pressure drop between the air inlet and outlet passageways.

Another feature of the present invention is the provision of an improved, rugged and highly effective check valve permitting the filling of the generator with fluid to be misted without interrupting the flow of air through the generator.

Other objects and features will be evident upon a perusal of the following description in which:

Fig. 1 is a plan view of the aerosol generator;

Fig. 2 is a sectional elevation view of the upper portion of the generator along line 2—2 of Fig. 1;

Fig. 3 is a sectional elevation view of the generator along line 3—3 of Fig. 1; and

Fig. 4 is a sectional elevation view of the upper portion of the generator along line 4—4 of Fig. 1.

For purposes of the present application, it will be assumed that a lubricating oil is being suspended in air to form oil mist aerosol. However, the scope of the application is not to be limited thereby.

In general, the generator comprises an upper head, a lower oil reservoir secured to the head, air inlet and outlet passageways in the head, an aerosol generating air passageway between the inlet and outlet chambers, an oil lift passageway extending from the oil reservoir into the aerosol generating passageway and a spring-biased air bypass between the air inlet and outlet chambers.

More particularly, the generator includes a head 1 (Fig. 3) preferably formed from a zinc die casting. The upper portion of the head 1 is generally annular with a substantially square flange 2 being provided at its lower end. A base 80 closes the upper end of the head.

A cup-shaped oil reservoir 3 is secured to the flange 2. The oil reservoir 3 is preferably made from a transparent plastic such as styrene acrylonitrile copolymer. The upper end of the oil reservoir 3 is provided with an annular flange 4. A generally square retaining element 5, having

2

an internal bore and counterbore matching the upper peripheral surface and flange of the retaining element 3, and four bolts 6 secure the reservoir 3 to the head 1.

A cylindrical disc 7 separates an oil reservoir chamber 8 of the oil reservoir 3 from an aerosol chamber 9 in the lower portion of the head 1. A pair of annular gaskets 10 provide a seal between the head 1, the disc 7 and the reservoir 3.

The base 80 of the head 1 includes a downwardly projecting boss 81 defining an inlet passageway 11 (Fig. 2) and a generally coaxial outlet passageway 12. A bypass aperture 13 is provided between the passageways 11 and 12. A ball check 14 is seated on the downstream edge of the aperture 13. A spring 15 held under compression between the ball check 14 and a retaining disc 16 screwed into the outlet passageway 12 maintains the ball check 14 on its seat under a predetermined pressure.

The aperture 13 and the spring-biased ball check 14 provide a constant pressure drop between the inlet passageway 11 and the outlet passageway 12. Thus, with higher pressures at the inlet 11 there will be correspondingly higher pressures in the outlet 12. Consequently, the volume of air passed through the generator can be increased merely by increasing the inlet pressure.

An aerosol generating passageway means 17 is connected in parallel with the bypass aperture 13. The passageway means 17 comprises a bore 18 and a counterbore 19, transverse to the inlet passageway 11, the aerosol chamber 9, and an aperture 20 at the bottom of passageway 12. The axis of the bore 18 and the counterbore 19 are disposed in a horizontal plane and are perpendicular to the axis of the inlet passageway 11 as best shown in Fig. 3. Hence, it can be seen that the bore 18 and the counterbore 19 connect the inlet passageway 11 directly to the aerosol chamber 9.

The aperture 20 is formed in the lower portion of the outlet passageway 12 adjacent the latter's connection with the inlet passageway 11 as best shown in Fig. 2. Thus, the aperture 20 connects the outlet 12 directly to the aerosol chamber 9. Hence, it will be appreciated that incoming air at the inlet passageway 11 (Fig. 3) will flow through the counterbore 19 and the bore 18 into the aerosol chamber 9 and thence through the aperture 20 (Fig. 2) into the outlet passageway 12.

When the inlet pressure is sufficiently high to unseat the ball check 14 against the force of its spring 15, air will also flow from the inlet passageway 11 through the aperture 13 and into the outlet 12.

An oil lift passageway means 21 (Fig. 4) is provided between the oil reservoir 3 and the transverse bore 18 in the aerosol generator passageway means 17. The passageway means 21 includes an oil lift tube 22 pressed into a vertical bore 23 in the head 1 and extending through the chamber 9 and an aperture 24 in the disc 7 into the oil reservoir chamber 8. An O-ring 25 provides a seal between the chambers 8 and 9. A retainer 26 and a compression spring 27 hold the O-ring 25 in sealing relation with the disc 7 and the tube 22.

A ball check 28 is disposed in a counterbore 29 coaxial with a bore 23. The ball check 28 seats itself on the shoulder 30 under the force of gravity. The function of the ball check 28 will be described later.

Immediately above the counterbore 29, the head 1 is provided with a vertical, generally annular boss 31. An elongated oil sight tube 32 is disposed within the boss 31 and extends upwardly therefrom. The oil sight tube 32 is preferably made from a transparent plastic such as styrene acrylonitrile copolymer. The lower end of the oil sight tube 32 is provided with a flange 33. A generally annular sleeve 34 is screwed into the inner threaded periphery of the boss 31 in the telescopic relation with the oil sight tube 32 to engage the upper sur-

face of the flange 33 holding the oil sight tube 32 secured in place. A gasket 35 provides a seal between the oil sight tube 32 and the head 1.

An aperture 36 is provided in the gasket 35 immediately above the counterbore 29 in the head 1. A generally vertical passageway 37 in the oil sight tube 32 is fluid conducting in relationship with the aperture 36 and the counterbore 29. A transverse passageway 38 is connected to the upper end of passageway 37. A generally vertical passageway 39 (Fig. 3) is connected to the end of the passageway 38 opposite to its connection with the passageway 37. A vertical passageway 40 and a generally horizontal passageway 41 in the head 1 interconnect the passageway 39 of the oil sight tube with a passageway 42 of an aerosol nozzle 43. The nozzle passageway 42 extends through the length of the nozzle 43 to the bore 18 in the aerosol producing passageway means 17.

A filter 44 is provided at the lower end of the oil lift tube 22.

The nozzle 43 is generally annular with a series of progressively necked down portions from its inlet to its outlet end. Similarly, the passageway 42 within the nozzle 43 is progressively smaller in a series of steps from its inlet to its outlet end. The inlet end of the nozzle 42 is pressed into a bore 45 and a counterbore 46 in the head 1 transverse to the inlet passageway 11. The nozzle 43 extends through the passageway 11 adjacent the aperture 13 and into the bore 18 and the counterbore 19. A threaded plug 71 closes the passageway 41 from atmosphere.

The outer periphery of the left-hand end (Fig. 3) of the nozzle 43 and the inner periphery of the right-hand end of the bore 18 form a short annular venturi 47 coaxial with the oil passageway 42 of the nozzle 43.

Due to the restricted venturi 47 in the aerosol generator passageway means 17, only a relatively small part of the air passing through the aerosol generator will pass through the aerosol generator passageway means 17 during normal high rates of air flow. The flow of air through the aerosol passageway generating means 17 will be substantially constant for inlet pressures higher than that which causes the ball check 14 to unseat to bypass air around the passageway means 17.

The air flowing from the venturi 47 into the bore 18 creates an extremely effective suction at the outlet end of the nozzle 43. As will be described below, the surface of the oil in the oil reservoir 3 is subjected to outlet pressure which is higher than the pressure at the outlet end of the nozzle 43 whereby oil is drawn by suction from the oil reservoir 3 into the bore 18 where it is misted with the air expanding from the venturi 47 into bore 18. With the concentric nozzle and venturi structure provided by the applicant, more efficient misting is effected. The inner wall surface of the head 1 facing the bore 18 acts as a baffle means for condensing undesirable heavy globules from the aerosol.

The means provided for filling the reservoir without interruption of air flow through the generator will now be described.

The disc 7 has an aperture 48 (Fig. 4) normally connecting the aerosol chamber 9 and the oil reservoir chamber 8. A bore 49 is provided in the head 1 coaxial with the aperture 48. At the upper end of bore 49 is a threaded counterbore 50.

A generally annular sleeve 51 is reciprocably disposed within the bore 49 and projects through the aperture 48. An O-ring 52 held in an annular groove 53 at the upper end of the sleeve 51 provides a seal between the sleeve 51 and the head 1. The sleeve 51 is provided with a central flange 54 which engages the shoulder surface 55 of the head 1 to prevent the sleeve 51 from being forced through the bore 49 and out of the head 1 under aerosol pressure. A spring 56 held under compression between

the upper surface of the disc 7 and the lower surface of the flange 54 urges the sleeve upwardly.

A necked down portion 57 at the lower end of the sleeve 51 includes a valve means 58 for closing the aperture 48 during filling of the oil reservoir 3. The valve means 58 comprises a shallow cup-shaped retainer 59 pressed on the necked down portion 57. An O-ring 60 is disposed around the necked down portion 57 and is held between the retainer 59 and a shoulder 61 at the upper end of the necked down portion 57.

A generally C-shaped lock washer 62 pressed into a groove 63 in the necked down portion 57 holds the O-ring 60 and the retainer 59 securely in place.

A filler plug 64 is threaded into the counterbore 50. An O-ring 65 is held in an annular groove 66 at the lower end of the filler plug 64. The O-ring 65 provides the effective seal between the filler plug 64 and the head 1.

In the closed position of the filler plug 64 as shown in Fig. 4, the bottom surface of the plug 64 engages a top surface of the sleeve 51 to force the sleeve 51 downwardly, opening the annulus of the aperture 48 surrounding the sleeve 51. When the plug 64 is removed, the spring 56 and aerosol pressure in the chamber 9 acting on the lower surface of the flange 54 force the sleeve 51 upwardly until the O-ring 60 engages the disc 7 to tightly seal the annulus of the aperture 48 surrounding the sleeve 51.

With the plug 64 removed, lubricant can be poured through the counterbore 50, the bore 49, and an axial passageway 67 in the sleeve 51 into the oil reservoir chamber 8. When the chamber 8 is filled, the plug 64 is replaced in the counterbore 50, thereby opening the annulus of the aperture 48 surrounding the sleeve 51 to again subject the surface of the oil to outlet pressure.

It will be noted that, when the plug 64 is removed as described above to seal the O-ring 60, the oil reservoir chamber 8 has outlet pressure therein. Consequently, as the plug 64 is removed this pressure is vented to atmosphere through the passageway 67, the bore 49 and the counterbore 50. However, this venting is prevented from splattering oil in the area surrounding the filler plug 64 by the gradual protected venting construction.

More specifically, the filler plug 64 (Fig. 4) has a necked down lower portion 68 below its threaded portion 69. Also, the counterbore 50 is slightly greater in diameter than the bore 49 and has a tapered lower edge 70. As the fluid plug 64 is unscrewed, the O-ring 65 gradually breaks its seal at the tapered edge 70. If there is a tendency of oil or aerosol to splatter through the broken seal, it will be dissipated on the lower shoulder of the threaded portion 69 and along the peripheral length of the threaded portion 69.

Consequently, there is no appreciable splattering of oil or aerosol around the generator when the plug 64 is removed.

It will be noted that, subsequent to the venting of the oil reservoir chamber 8 as described above, the O-ring 60 effectively prevents aerosol pressure from entering the chamber 8. The ball check 28 seats to prevent reverse flow of air or aerosol through the oil lift tube 22.

A vertical bore 72 (Fig. 3) and a threaded counterbore 73 are provided in the boss 31 adjacent the oil sight tube 32. A needle valve 74 for adjusting the oil flow in the passageway means 21 is screwed into the counterbore 73. The needle valve 74 seats on the upper edge of the bore 72. When the valve 74 is turned to raise from the bore 72, aerosol from the chamber 9 is admitted into the passageway 41 in the oil passageway means 21 to reduce the vacuum therein. The more the vacuum is reduced, the slower the rate of oil flow.

While there has been described what is at present believed to be the preferred embodiments of the invention, it will be understood that various modifications may be made therein; and it is contemplated to cover

in the appended claims all such modifications as fall within the true spirit and scope of the invention.

What is claimed is:

1. An aerosol generating device of the type in which fluid in a reservoir, subjected to a pressure greater than atmospheric pressure, is caused to flow into an aerosol generating passageway to be suspended in aerosol form in a fluid passing through the passageway, and in which means is provided for filling the reservoir during operation of the device, wherein said means comprises an element separating the reservoir from a source of fluid pressure higher than atmospheric pressure, an aperture in the element normally interconnecting the source of fluid pressure with the reservoir to subject the reservoir to a pressure higher than atmospheric pressure, a bore in the device generally coaxial with the aperture, a generally annular sleeve reciprocally disposed within the bore and extending through the aperture, and an O-ring secured to one end of the sleeve and engageable with the element for closing the aperture in one position of the sleeve, biasing means urging the sleeve to said one position, and a removable filler plug in the bore engaging the sleeve in a closed position of the plug to move the sleeve to a second position unseating the O-ring from the element.

2. The combination claimed in claim 1 wherein a counterbore is provided immediately adjacent the bore with a tapered shoulder connecting the bore and counterbore, and wherein the filler plug includes a threaded portion of one diameter for threading engagement with a complementary threaded inner periphery of the counterbore, a necked down portion extending into the bore in the closed position of the plug, an annular groove in the necked down portion of the plug, and an O-ring disposed in the groove normally under compression between the surface of the groove and the adjacent periphery of the bore, said O-ring gradually breaking the seal between the plug and the device as the O-ring rides over the tapered shoulder upon removal of the plug, the lower surface of the threaded portion of the plug and the threaded periphery of the plug and counterbore dissipating the force of aerosol initially vented from the reservoir to atmosphere upon removal of the plug.

3. An aerosol generator comprising an inverted generally cup-shaped cast head portion and a generally cup-shaped reservoir secured in sealing relation to the bottom of the head portion, the interior of the head portion at least partially defining an aerosol chamber, an internal boss projecting downwardly from the base of

the head portion and defining substantially coaxial inlet and outlet passageways, passageway structure in the boss including a spring biased check valve connecting the inlet passageway directly to the outlet passageway, the boss defining a generally horizontal bore transverse to the inlet passageway and connecting the inlet passageway to the aerosol chamber, an elongated generally cylindrical nozzle carried by the boss with its outlet end projecting partially into the bore in close proximity to the inner periphery of the bore to form a generally annular venturi surrounding its outlet end, liquid passageway structure connecting the other end of the nozzle with the lower portion of the reservoir, the side wall of the head portion adjacent the bore providing a baffle means for condensing undesirable heavy globules from the aerosol.

4. The combination claimed in claim 3, wherein the boss defines a second bore coaxial with the first-mentioned bore and extending outwardly from the inlet passageway at a position diametrically opposite the first-mentioned bore, the second bore defining a liquid chamber in the liquid passageway, the liquid chamber receiving the other end of the nozzle in sealing relation, the boss defining a valve aperture connecting the liquid chamber with the higher pressure aerosol chamber, and an adjusting screw carried by the head portion and projecting into the valve aperture for adjusting the valve aperture opening to control the rate of flow of liquid from the reservoir to the nozzle.

5. The combination claimed in claim 4 wherein the liquid passageway structure includes a transparent sight tube carried by the head portion, the tube defining a passageway with a restricted portion followed by an enlarged portion vertically below the restricted portion to cause a liquid to flow through the enlarged portion in droplet form whereby the rate of liquid flow may be observed.
